UNITED STATES PATENT OFFICE.

ENOS L. WALKER, OF ST. LOUIS, MISSOURI.

WOODEN VENEER BERRY-BOX.

SPECIFICATION forming part of Letters Patent No. 729,982, dated June 2, 1903.

Application filed March 9, 1903. Serial No. 146,014. (No model.)

To all whom it may concern:

Be it known that I, ENOS L. WALKER, a citizen of the United States, residing at St. Louis, State of Missouri, have invented certain new and useful Improvements in Wooden Veneer Berry-Boxes, of which the following is a specification containing a full, clear, and exact description, reference being had to the accompanying drawings, forming a part hereof.

10 My invention relates to improvements in wooden veneer berry-boxes; and it consists of the novel construction, combination, and arrangement of parts hereinafter shown, described, and claimed.

15 The object of this invention is to improve upon Letters Patent No. 512,571, granted to me on the 9th day of January, 1894.

In the drawings, Figure 1 is an end view of my improved berry-box. Fig. 2 is a top plan view of the same. Fig. 3 is a bottom plan view of the blank with parts broken away.

Referring to the drawings, 1 indicates the outside end flaps, and 2 the inside end flaps. The outside end flaps 1 have smooth abutting edges 3, and when the box is formed the ends of said flaps bear against each other, as illustrated in Fig. 1, and are held in such relation after the box has been completed. The said outside end flaps form a truss structure

30 to strengthen the box against side compression. To strengthen the ends of the box against outward pressure of the contents which may be placed within the box and also from pressure which may be applied to the outside of the end, I employ in the construction of my box a stiffening-strip 4, and said stiffening-strip 4 is adapted to fit snugly in the box, as illustrated in Figs. 1 and 2, and occupies a position between the outside end flaps 1 and the inside end flaps 2. While this stiffening-strip 4 has the function as above described, in view of the fact that it is made to fit snugly in the end of said box and between the sides 5 and 6 of the same it has the 45 additional function of strengthening the ends of the box against side compression or a similar function, as heretofore described as relating to the outside end flaps 1. The inside end flaps 2 are tapered and act as a "former" 50 when turned up in the construction of the box, so as to hold the sides 5 and 6 in a flaring position, and while the inside end flaps 2

have the function as above set forth they might be said to have an additional function of taking up side compression of the ends of 55 the box.

By constructing a box as above described, wherein the outside end flaps 1 are abutted and held against each other and form a truss structure, and by the employment of the 60 stiffening-strip 4 and the inside end flaps 2 it will be seen that I have constructed a berry-box out of wooden veneer material which has its ends strengthened against side compression and against any ordinary pressure from 65 the inside or outside of the ends of the box.

In view of the fact that my invention is especially designed for the transportation of strawberries and other perishable and delicate fruits it is necessary that the box should 70 be as rigid as possible, so that the ends or sides will not expand, allowing the fruits to "work down" and pack in the box, thereby crushing the same. Then, again, if the box after being built is susceptible of expansion 75 such a box when filled and transported a long distance will have the appearance at its destination of not being filled, so it is absolutely necessary in a box designed for this purpose that it should be perfectly rigid as far as it 80 can be made.

In the construction of my box I take a wooden piece of veneer, a portion of which is illustrated in Fig. 3 (and the remaining portion of which would be a duplicate of 85 what is shown in Fig. 3) and form therein slits 7 and 8, making the outside end flaps 1 and inside end flaps 2. I also form in proximity to the outside end flaps 1 scores 9 and 10 and in proximity to the inside end flaps 2 90 scores 11 and 12. It will be noticed in this connection that the scores 9 and 10 are spaced apart farther than the scores 11 and 12, so as to provide for the flaring of the sides of the box and also to compensate for the thickness 95 of the end flaps 2 and the stiffening-strip 4. In other words, where the scores 9 and 11 and 10 and 12 approach each other they lie in planes apart of twice the thickness of the veneer. After the veneer blank has been 100 scored and slitted, as hereinbefore described, to form the box the inside end flaps 2 are first turned up. Then the sides 5 and 6 are turned up against the edges of the inside end

flaps 2. Then the outside end flaps 1 are brought together on the outside of the inside end flaps 2, their free edges abutting against each other. The stiffening-strip 4 is then inserted between the outside end flaps and the inside end flaps, and by means of staples 13, driven through the outside end flaps 1, the stiffening-strip 4, and the inside end flaps 2, the ends of the box are fastened.

10 Having fully described my invention, what I claim is—

A wooden veneer berry-box having a flaring mouth, formed from a veneer blank comprising side flaps 5, 6, inside end flaps 2, 2, for 15 the opposite ends of the box and outside end flaps 1, 1, whose ends abut against each other, and the separate stiffener-strips 4, 4, passing from the inside corners of the opposite sides

of the box and located between the said inside and outside end flaps, the veneer blank 20 being scored along lines 11, 12, at the lower edges of the inside end flaps and along the lines 9, 10, where the outside end flaps 1, 1, join the side flaps of the box, scores 9 and 11, and 10 and 12, being out of line with each 25 other a distance equal to the combined thickness of an end flap 2 and a stiffening-strip 4, substantially as and for the purposes set forth.

In testimony whereof I have signed my 30 name to this specification in presence of two subscribing witnesses.

ENOS L. WALKER.
